UNITED STATES PATENT OFFICE.

WILLIAM BUHL, OF MINNEAPOLIS, MINNESOTA.

WRENCH.

No. 823,390.

Specification of Letters Patent.

Patented June 12, 1906.

Application filed June 9, 1905. Serial No. 264,499.

To all whom it may concern:

Be it known that I, WILLIAM BUHL, a citizen of the United States, residing at Minneapolis, in the county of Hennepin and State of Minnesota, have invented new and useful Improvements in Wrenches, of which the following is a specification.

The invention relates to an improvement in wrenches, particularly sliding-jaw wrenches, comprehending specifically improvement in the means for operating the sliding jaw.

The main object of the invention is the production of simple and effective means whereby the sliding jaw of the wrench may be easily and quickly adjusted to the desired position.

The preferred embodiment of details of structure will be described in the following specification and are clearly illustrated in the accompanying drawings, in which—

Figure 1 is a view in elevation of a wrench embodying the preferred form of my improved operating mechanism. Fig. 2 is a longitudinal central section of the same, parts being shown in elevation. Fig. 3 is a transverse section of the same on the line 3 3 of Fig. 2. Fig. 4 is a perspective view of the thread-engaging projection secured to the shank of the wrench. Fig. 5 is a view in elevation with the wrench-shank broken off of a modified form of operating mechanism. Fig. 6 is a longitudinal section of the same. Fig. 7 is a transverse section on the line 7 7 of Fig. 6. Fig. 8 is a broken sectional view, partly in elevation, of another form of operating means.

Referring particularly to Figs. 1 to 4 of the drawings, my improved wrench comprises a fixed jaw 1, supported at the upper end of the shank 2, to the lower end of which is fixed the handle 3, all of which parts may be of any usual or preferred form. The sliding jaw comprises a jaw proper, 4, formed integral with and on the upper end of the jaw-barrel 5, which barrel is arranged to slidably engage the wrench-shank 2. 6 represents the operating-screw having a portion 7 formed with ordinary screw-threads and arranged for threaded engagement with an opening 8, formed in the base-flange 9 of the barrel. To the screw 6, beyond the barrel, is secured an operating-head 10, whereby the screw may be revolved, that portion of the screw within the barrel formed with a worm-thread 11, arranged to engage a projection 12, suitably secured to the wrench-

shank 2 and comprising a laterally-projecting plate 13, having a suitably-formed edge 14 to engage the worm-thread 11. In the operation of this form of the wrench revolution 60 of the screw 6 under the influence of the nut 10 will cause a slight longitudinal movement of the screw, due to the threaded connection with the opening 7, this revolution of the screw causing the projection 12 to 65 ride in the worm-threads, and as the worm-threads are of considerably greater pitch than the threads 7 the sliding jaw will be moved lengthwise the shank 2 quite rapidly.

The comparative lengthwise movement 70 of the sliding jaw is controlled solely by the variation in pitch between the worm-threads and the ordinary threads, it being possible to so form the worm-threads that a single revolution of the nut 10 will move the 75 sliding jaw a considerable distance lengthwise the shank.

In Figs. 5, 6, and 7 the wrench comprises a fixed jaw 15, having a plurality of faces 16 and 17 arranged, respectively, for engagement with the plane nut or with a pipe. The sliding jaw 18 is arranged with cooperative faces 19 and 20 and is secured to a depending barrel 21, within which barrel at diametrically opposite points are arranged screw-rods 85 22, having worm-threads 23 for engagement with projections 24, the lower end of the screw-rods having threaded connection at 25 26 with the base-flange of the barrel, all as described in the preferred construction. For 90 simultaneous operation of the screw-rods 22, however, I prefer to secure on each of said rods beyond the barrel a gear-pinion 27, which pinions are arranged to intermesh with the gear-face 28 of an annular operating 95 member 29, supported for operation by the shank. Revolution of the annular member 29 will, through the medium of the gear-pinion 27, revolve screw-rods 22, adjusting the sliding jaw lengthwise the shank, as in the 100 preferred form.

In Fig. 8 the construction is similar in all respects to the preferred form except that the projection for co-operation with the worm-gear of the screw-rods 6 comprises a block 30, recessed on its vertical face at 31, in which recess is seated a ball 32, designed to engage the worm-threads and move the sliding jaw 4 lengthwise of the shank 2 when the screw-rod has been revolved.

In each of the constructions described it will be noted that the main adjustment of the

sliding jaw is obtained through the variation in pitch of threads formed on a single screw-rod, the threads of smaller pitch having engagement with the sliding jaw, while the 5 threads of the larger pitch have engagement with a fixed stop or projection carried by the shank of the wrench.

If preferred, I contemplate the use of a coil-spring 33, encircling the rod 11 intermediate the knee-head 9 and the nut 10, and also a coil-spring between the nut 10 and the nut 34, which has the usual function of a lock-nut, though this latter feature is not illustrated.

15 Having thus described the invention, what is claimed as new is—

1. A wrench having a fixed jaw and a shank, a movable jaw slideable lengthwise the shank, and an operating-rod having threaded 20 connection with the movable jaw and with the shank within the movable jaw, the threads of the latter connection being of greater pitch than the threads of the former connection.

25 2. A wrench having a shank, a jaw fixed thereto, a jaw movable thereon, a screw-rod having threaded connection with the movable jaw, said rod being formed within the jaw with worm-threads of greater pitch than 30 the threads connecting said rod and the movable jaw, and a projection carried by the shank and arranged to engage said worm-threads.

3. A wrench having a shank, a jaw fixed 35 thereto, a jaw movable thereon, a screw-rod

formed with two sets of threads, the pitch of one set being greater than the pitch of the other, one set of threads engaging the movable jaw and the other set being arranged within the movable jaw and engaging the shank.

40

4. A wrench having a shank, a jaw fixed thereto, a jaw movable thereon, a screw-rod formed at its lower end for threaded connection with the jaw, the upper end of the rod within the jaw being formed with a worm-thread, and a projection fixed to the shank and engaging said worm-thread.

45

5. A wrench having a shank, a jaw fixed thereto, a jaw movable thereon, a screw-rod formed at its lower end for threaded connection with the jaw, the upper end of the rod within the jaw being formed with a worm-thread, a projection fixed to the shank and engaging said worm-thread, and means for revolving the screw-rod.

50

6. A wrench having a shank, a jaw fixed thereto, a jaw movable thereon, a barrel depending from said movable jaw, a screw-rod having threaded connection with the barrel and extending upwardly therein, a nut fixed 60 on the rod beyond the barrel, that portion of the rod within the barrel being formed with a worm-thread, and a projection secured to the shank and engaging said worm-thread.

65

In testimony whereof I affix my signature in presence of two witnesses.

WILLIAM BUHL.
